CLAIM

The ornamental design for a carton for oral care composition as shown and described.

DESCRIPTION

FIG. 1 is a perspective view of a carton for oral care composition, embodying the new design;

FIG. 2 is a front view thereof;

FIG. 3 is right view thereof;

FIG. 4 is back side view thereof;

FIG. 5 is a left side view thereof;

FIG. 6 is a top view thereof; and,

FIG. 7 is a bottom view thereof.

In the drawings, the evenly-spaced broken lines depict portions of the carton for oral care composition that form no part of the claim. The dash-dot-dash broken lines define a boundary of the claimed design and are not themselves part of the claimed design.
